UNITED STATES PATENT OFFICE

168,989

DISPLAY CASE FOR SHEET MATERIAL

Harry Fund, St. Louis, Mo.

Application November 8, 1952, Serial No. 22,205

Term of patent 7 years

(Cl. D80—11)

To all whom it may concern:

Be it known that I, Harry Fund, a citizen of the United States, residing in the city of St. Louis and State of Missouri, have invented a new, original, and ornamental Design for a Display Case for Sheet Material, of which the following is a specification, reference being had to the accompanying drawing, forming a part thereof.

In the drawing:

Fig. 1 is a front elevational view of a display case for sheet material showing my new design;

Fig. 2 is a side view with a portion of the case shown in section as indicated by the line 2—2 of Fig. 1, and

Fig. 3 is a top plan view thereof.

The rear of the case is substantially plain in appearance.

I claim:

The ornamental design for a display case for sheet material, substantially as shown and described.

HARRY FUND.
